ACTUATING MEANS FOR FASTENER
DRIVING MACHINES

John G. Soave, Long Island City, N. Y., assignor
to Waldes Kohinoor, Inc., Long Island City,
N. Y., a corporation of New York

Application December 29, 1950, Serial No. 203,370

4 Claims. (Cl. 1—3)

1

This invention relates to improvements in actuating means for presses of the swinging head type, and more particularly to an improved means for positively actuating the swinging head of such a press throughout its full angular movement from a rest to a working position with respect to a fixed anvil.

Presses as aforesaid are conventionally used to apply end stops to a slide fastener, such end stops being in the form of a staple whose prongs are driven through and affixed to the fastener tapes at the end of the fastener, usually the bottom end, to prevent movement of the slider past the end-most fastener elements. In its swinging movement from its rest to its working position in which it impacts the anvil, the head is adapted to transfer a staple from a hopper and, finally, to set it in the tapes of the fastener which is supported on the anvil.

Heretofore, the head of such a press was actuated in its swinging movement by a force generated by the operator through depression of a foot pedal and which was transmitted to the head through a reciprocable drive rod pivotally connected at one end thereof to the head and at its other end to the foot pedal. Obviously, a force generated by foot pressure on a pedal is or may be irregular, giving rise to certain objections in the use of an end-stop applying press, among which may be noted that if the applied foot pressure is too small, the hammer end of the head will not impact the anvil with a force sufficient to properly set the staple and, if too large, the force with which the head impacts the anvil can be so great as to damage the fastener tapes. Moreover, the direct connection of a drive rod to a head mounted to swing in a descending arc on its power or working stroke is objectionable, since analysis will show that with such form of drive connection the head attains its greatest velocity as it approaches the anvil, with the result that its force of impact on the anvil, being uncontrollable in the sense that it depends on the varying pressure applied to the foot pedal, may far exceed that required for properly setting the staple.

Stated broadly, a principal object of the present invention is the provision of a simple yet highly effective means for actuating the swinging head of a press as described which overcomes the above-noted objections incident to foot operation and which also effects a controlled movement of the swinging head, giving a lowering velocity and a corresponding increase in power of the head as it approaches the anvil, with the result that the smoothness and uniformity of press operation is

2

greatly improved as compared to prior presses serving similar function.

More particularly, the invention aims to provide solenoid means for imparting the actuating force to the drive rod of the head operating mechanism, in conjunction with a toggle-joint form of drive connection between the drive rod and the swinging head, wherein the solenoid means functions consistently and uniformly to generate the predetermined force required positively to actuate the head throughout its working stroke, and the toggle-joint driving connection operates to translate said force into a high initial but a lowering velocity as it approaches the anvil, such lowering velocity being accompanied by a corresponding increase in power.

Another object of the invention is the provision of solenoid means for generating and imparting the head actuating force to the drive rod of a press actuating means as aforesaid, which is so constructed and arranged as to permit the use of relatively inexpensive standard commercial solenoids, the stroke of whose armatures is less than the predetermined axial movement of the drive rod required to actuate the head from its rest to its working position.

A more specific object of the invention is the provision of an improved actuating means for the swinging head of a press of the stated character employing two standard commercial solenoids which are so connected that they operate in series in imparting the predetermined axial movement of the drive rod required to actuate the head from its rest to its working position.

Yet another object of the invention is the provision of solenoid means for effecting the predetermined axial movement of the drive rod of a press-head actuating means as aforesaid, which employs two standard commercial solenoids connected in series and coupled in such manner that one of the solenoids imparts a portion (for example one-half) of the predetermined movement required of the drive rod and simultaneously therewith conditions the second solenoid for operation, and that the second solenoid following its conditioning as aforesaid imparts the balance of said drive rod movement.

A still further object of the invention is the provision of solenoid means for applying the force required to actuate the swinging head of a press from its rest to its working position which employs two standard commercial solenoids whose armatures each have a stroke less than that required for head actuation, and a coupling be-

tween the armatures which effectively totals the motion of both solenoid armatures to a sum corresponding to that required for actuating the swinging head throughout the full extent of its swinging movement.

Other objects and features of advantage of the improved press-head actuating means of the invention will be seen from the following detailed description thereof, taken with the accompanying drawings, in which:

Fig. 1 is a side elevation, partly in section, of a swinging head type of press employing solenoid actuating means therefore according to the present invention, the view illustrating the head in its normal or rest position, the solenoid armatures in their corresponding inactive or raised position, and the special coupling means connecting said armatures;

Fig. 2 is a detail view illustrating the solenoid armatures in an intermediate position; and

Fig. 3 is a view similar to Fig. 1 illustrating the swinging head in its working position, and both solenoid armatures in their fully attracted positions.

Referring to the drawings, the illustrated press, except for its head-actuating means, is of the conventional type used for applying the staple-like end stops to the tapes of slide fasteners as aforesaid, and comprises a vertical press frame 10 having an offset arm 11 which mounts a vertically disposed anvil 12 on which a slide fastener is adapted to be positioned to receive the end stop. Operatively related to the anvil 12 is a sector-shaped head 13 mounted to swing about a fixed fulcrum 14 on the press frame. The working end of the head is formed as a hammer 13a which is adapted in the retracted or rest position of the head to receive the staple-like end stop from a hopper 15 and consequent to the swinging motion of the head to drive the prongs thereof throughout the tapes of the slide fastener positioned on the anvil and thereupon to set or clinch the end stop through engagement of the prongs with the anvil, all as well known in the art.

The head 13 is adapted to be actuated throughout its working stroke upon predetermined axial movement in the downward direction being imparted to a substantially vertically disposed drive rod 16 which is connected to the head through a toggle-joint form of driving connection. Such connection comprises a normally inclined lever 17 pivoted intermediate its ends to turn on a frame-mounted pin 18, the raised or rearward end thereof being connected to the upper end of the drive rod, and the lower or forward end thereof being pivotally connected at 19 to one end of a normally vertically disposed push link 20 whose upper end is pivotally connected to the head, it being observed from Fig. 1 that in the retracted position of the head the lever 17 and push link 20 have a normal acute angular relation. When drive rod 16 is actuated in downward direction an amount causing the lever 17 and the push link 20 to straighten out, i. e. to assume a substantially straight-line relationship, as seen in Fig. 3, the link 20 moves upwardly and imparts a force on the head, causing it to swing downwardly against the anvil 12. However, since upward movement of the pivot point 19 is accompanied also by rearward movement thereof (because the forward end of lever 17 moves rearwardly), there results an effective shortening of the push link 20 as it approaches its uppermost (Fig. 3) position, which results in a lowering in the velocity and a corre-

sponding increase in the power of the head as it approaches the anvil.

As distinguished from prior swinging head presses, wherein the force for imparting the predetermined axial movement to the drive rod is required for head movement is generated by foot pressure on a foot pedal, the present invention provides solenoid means for imparting the required drive rod movement, thus rendering press operation independent of irregularities in applied foot pressure and more smooth and uniform than heretofore. It is a further feature of the invention that the solenoid means employed comprise two standard commercial solenoids, the stroke of whose armatures under electro-magnetic attraction of their windings is less than the predetermined axial movement of the drive rod 16 required to actuate the press head throughout its full movement aforesaid, and a special lost-motion coupling between the armatures of said solenoids for translating the stroke of each solenoid armature into approximately half of the required drive rod movement.

To this end, the solenoid means of the invention comprises a first or lower solenoid 22 affixed by means of a bracket 23 to a vertical mounting plate 24 secured to the press frame 10 as by U-clamps 25, and a second or upper solenoid 26 also secured to said mounting plate by means of a bracket 27. The solenoids 22 and 26 are disposed in vertically spaced relation below the drive rod 16 and hence their armatures 28, 30 respectively are coaxially arranged with respect to one another, and generally with respect to the drive rod.

The solenoid armatures proper are fabricated from magnetic material, as usual, and are provided with non-magnetic stabilizing extensions 28a, 30a respectively which center and steady the armatures when they are in their raised position with respect to the windings of their solenoids, in which they are shown in Fig. 1. Normally, the armature 30 of the upper solenoid 26 is maintained raised above the magnetic field of its winding by its connection with the lower end of the drive rod 16, whose length is such that when the press head 13 is in its rest position (Fig. 1), the armature 30 is so raised and is thus normally inoperative, even though the winding of its solenoid is energized, since the armature is out of the electromagnetic field of its winding. Connection between the armatures 28, 30 is effected by an intermediate connecting link 32 extending between the lower end of the armature extension 30a and the upper end of the armature 28. To permit relative motion between said armatures, the coupling between the armature extension 30a and the armature 28 is of the pin and slot type providing for lost-motion movement between said armatures, the pin 33 being carried by the armature extension and the slot 34 being cut or otherwise formed in the connecting link 32. By reference to Fig. 3, the length of the slot is in excess of the stroke of the armature 30, and its lengthwise positioning along the length of the link is such that, as shown in Fig. 1, the pin normally engages the upper terminal edge of the slot and through the link supports armature 28 partially raised from the winding of its solenoid 22 but in the magnetic field thereof.

The operation of the solenoid actuating means as aforesaid is as follows: Upon both solenoids 22, 26 being energized, the upper solenoid 26 initially performs no useful work, since its armature 30 is disposed above and without the field of its

winding as aforesaid. However, the armature 28 of the lower solenoid is attracted and moves throughout its full stroke to a position illustrated in Fig. 2, such armature motion being transmitted to the drive rod 16 through link 32, coupling pin 33 and armature 30 of the upper solenoid, and thereby actuating the drive rod for a portion (approximately one-half) of the predetermined axial movement required for full press-head actuation. The motion of the armature 28 also lowers the armature 30 into the field of the upper solenoid (Fig. 2) and thereby effectively conditions the upper solenoid for operation. Since said solenoid is energized, the armature 30 is now attracted and moves throughout its stroke to its Fig. 3 position, completing the movement of drive rod. Due to the pin and slot coupling between armatures, the armature 30 may partake of its stroke without interference, since the pin and slot connection 33, 34 permits the armatures to contract axially.

Return movement of the swinging head 13 is accomplished by suitable spring or other means (not shown) which become effective upon the solenoids 22, 26 being deenergized. Such head movement returns the armatures 28, 30 to their raised position corresponding to the rest position of the head (Fig. 1) and completes the cycle of operation.

Energization of both the solenoids 22, 26 may be controlled as by a plunger operated switch contained in a switch box 36 affixed to the base of the frame, with its plunger 37 projecting through the lower end of the box in position to be engaged by the nose of a foot pedal 38 fulcrumed to said base. The solenoids 22, 26 are connected in a supply circuit (not shown) controlled by said plunger-operated switch, and hence the press head 13 is actuated throughout its working stroke by a mere touch of the foot on pedal 38. Other conveniently located and readily operated means for closing the solenoid supply circuit may of course be substituted.

It will be appreciated that the press head actuating means as described achieves the desirable objectives of the invention set forth in the foregoing by relieving the operator of the requirement of applying the actuating force through depression of a foot pedal and, instead, operating the drive rod of said actuating mechanism by solenoid means capable of applying uniform force and thus making for smooth and uniform press operation. The invention also provides a simple yet highly effective arrangement of two standard commercial solenoids, the stroke of whose armatures is only about one-half of that required, as the means for applying the requisite axial movement to the drive rod, which are so coupled that each solenoid supplies one-half of the required axial movement of the drive rod, thus overcoming shortness of armature stroke and thereby permitting the use of two inexpensive solenoids rather than an expensive, specially constructed single solenoid.

The invention also provides an improved form of driving connection between drive rod and swinging head which overcomes the noted objection of the head attaining its greatest velocity as it approaches the anvil which characterized the prior direct connection of drive rod to head. The improved toggle-joint driving connection aforesaid combines with the solenoid means for powering the head actuating linkage to give the same controlled and predetermined staple-setting pressure for repeated operations of the press, and

thus guarantees uniformity of staple-setting for the life of the press.

As many changes could be made in carrying out the above construction without departing from the scope of the invention, it is intended that all matter contained in the above description or shown in the accompanying drawings shall be interpreted as illustrative and not in a limiting sense.

10 I claim:

1. A press comprising a frame, an anvil mounted thereon, a sector-shaped head fulcrumed to the frame for swinging movement toward and away from said anvil, and means for actuating said head including a drive rod drivingly connected to said head and adapted upon predetermined axial movement thereof in one direction to actuate said head from a normal rest position to a working position in which it engages on said anvil, and a pair of solenoids mounted on said frame in vertically spaced relationship and with their armatures coaxially disposed to one another and generally to the drive rod, the armature of the upper solenoid being directly connected to said drive rod and to the armature of the other solenoid by a lost-motion connection.

2. A press comprising a frame, an anvil mounted thereon, a sector-shaped head fulcrumed to the frame for swinging movement toward and away from said anvil, and means for actuating said head including a drive rod drivingly connected to said head and adapted upon predetermined axial movement thereof in one direction to actuate said head from a normal rest position to a working position in which it engages on said anvil, and a pair of solenoids mounted on said frame in vertically spaced relationship and with their armatures coaxially disposed to one another and generally to the drive rod, the armature of the upper solenoid being connected to the lower end of the drive rod, which latter has length as to maintain said armature raised from the field of its winding when the head is in its rest position, and being connected at its lower end to the armature of the lower solenoid by a lost-motion connection normally maintaining said last armature within the field of its solenoid winding, said connection being operative upon energization of said solenoids to translate the stroke of said last armature into actuation of the drive rod through a portion of its predetermined axial movement and simultaneously therewith to lower the armature of the upper solenoid into the field of its winding, thereby rendering the upper solenoid effective to actuate the drive rod for the balance of said movement.

3. A press comprising a frame, an anvil mounted thereon, a sector-shaped head fulcrumed to the frame for swinging movement toward and away from said anvil, and means for actuating said head including a drive rod drivingly connected to said head and adapted upon predetermined axial movement thereof in one direction to actuate said head from a normal rest position to a working position in which it engages on said anvil, and a pair of solenoids mounted on said frame in vertically spaced relationship and with their armatures coaxially disposed to one another and generally to the drive rod, the stroke of each said armature under electromagnetic attraction of its field being less than the predetermined axial movement of the drive rod required to actuate said head throughout its full swinging movement aforesaid, and means interconnecting the armatures of said solenoids to one

another and to said drive rod in such manner that one of the solenoids is effective to actuate the drive rod for a portion of said predetermined axial movement and the other solenoid is effective to actuate the drive rod for the balance of said movement.

4. A press comprising a frame, an anvil mounted thereon, a sector-shaped head fulcrumed to the frame for swinging movement toward and away from said anvil, and means for actuating said head including a drive rod drivingly connected to said head and adapted upon predetermined axial movement thereof in one direction to actuate said head from a normal rest position to a working position in which it engages on said anvil; and a pair of solenoids mounted on said frame in vertically spaced relationship and with their armatures coaxially disposed to one another and generally to the drive rod, the stroke of each said armature under electromagnetic attraction of its field being less than the predetermined axial movement of the drive rod required to actuate the head throughout its full movement aforesaid, the armature of the upper solenoid being connected at its upper end to the 25 lower end of said drive rod, which latter has length as to maintain said armature raised from the field of its solenoid winding when the head is in its rest position, and being connected at its lower end through a pin and slot connection to 30

a link in turn connected to the upper end of the armature of the lower solenoid, said pin and slot connection and said link normally supporting the armature of the lower solenoid within the field of its solenoid winding, the construction and arrangement being such that energization of said solenoids results in the armature of the lower solenoid partaking of its stroke and imparting a portion of said predetermined axial movement to said drive rod through the intermediate link and the armature of the upper solenoid, and a corresponding movement of the latter armature into the field of its solenoid winding, and thereupon in the armature of the upper solenoid partaking of its stroke and imparting the balance of said predetermined axial movement to said drive rod.
